UNITED STATES PATENT OFFICE.

WALLACE M. GRAY, OF CINCINNATI, OHIO, ASSIGNOR TO THE AMERICAN VALVE AND METER COMPANY, OF CINCINNATI, OHIO, A CORPORATION OF OHIO.

AUTOMATIC SWITCH STAND.

Application filed March 1, 1927. Serial No. 171,899.

My invention relates to improvements in automatic switch stand. One of its objects is to provide an automatic switch stand adapted to be thrown by hand and also to be thrown automatically by a locomotive or car, and provided with new and improved and reliable apparatus for such purpose. Another object is to provide an improved automatic switch stand of the low down type, in which no movement of levers exteriorly of the switch stand casing occurs when the switch is thrown automatically. Another object is to provide a stronger, more reliable and less expensive automatic switch stand apparatus, and one which is better able to meet all of the requirements of such apparatus without liability to failure or to result in accidents. My invention also comprises certain details of form and arrangement and combination of components, all of which will be fully set forth in the description of the accompanying drawings, in which:

Fig. 1 is a vertical section through an automatic switch stand apparatus embodying my invention.

Fig. 2 is a plan view of the apparatus shown in Fig. 1 with portions of the casing broken away.

Fig. 3 is a perspective view of the actuating shaft detached.

Fig. 4 is a perspective view of a spring actuated cam member movable endwise upon the actuating shaft.

Fig. 5 is a perspective view of a rocker member or cam disk member detached.

Fig. 6 is a perspective view of a transmitting ring member, detached.

Figs. 7, 8 and 9 are diagrammatic views illustrating different operative positions of my improved automatic switch mechanism.

The accompanying drawings illustrate the preferred embodiment of my invention in which 15 represents the lower section of the switch stand casing and 16 represents the upper section of said casing. The sections 15 and 16 are secured together by means of bolts 17, and the line of division between said sections is substantially horizontal and parallel with the axis of the actuating shaft 18, so as to form two-part journal bearings 19 and 20 in which said shaft 18 is rotatably supported at opposite ends. The lower cas-

ing section 15 is provided with external ribs 21 along its opposite sides by means of 55 which it may be firmly attached to railway ties at one side of the switch to be actuated. A weighted actuating lever 22 is rigidly attached to one end of the actuating shaft 18, and is adapted to be swung or turned 60 through an arc of one hundred and eighty degrees from a horizontal position at one side of the shaft 18 to a horizontal position at the opposite side of the shaft 18, carrying the shaft 18 with it through one half of a 65 rotation of said shaft.

The middle portion of the shaft 18 is preferably polygonal and has a transverse perforation 24. A rocker member, disk, or short cylinder 25 is centrally perforated to 70 receive the shaft 18 and is hinged or pivotally mounted upon the shaft 18 by means of a hinge pin or transverse axle 26, which passes through the transverse perforation 24 in the shaft 18 and through perforated 75 bosses or enlargements 27 carried by the disk 25 and located upon opposite sides of the shaft 18. The enlargements 27 of the disk 25 upon one side thereof are extended outwardly to form obtuse wedge shaped 80 cams 28. The disk 25 and cams 28 have a free rotary movement upon the pin 26 through an arc of say sixty or ninety degrees, being limited by engagement of the disk with the shaft 18 against a movement 85 of greater arc than sixty or ninety degrees, as the case may be.

A sleeve 30 is mounted non-rotatably upon the shaft 18 to move endwise thereon. The sleeve 30 is provided at one end with a 90 pair of obtuse wedge shaped cams 31 which are in position upon opposite sides of the shaft 18 so as to be engaged by the cams 28 of the disk 25. The sleeve 30 is also provided with a flange 32 against which one 95 end of a coiled spring 33 bears to force the cams 31 yielding into engagement with the cams 28. The opposite end of the spring 33 bears against a nut 34 threaded upon one end of the shaft 18 and held 100 rigidly in its adjusted position thereon by a lock nut 35. The shaft 18 is preferably provided at one end with a shoulder 36 which limits endwise movement in one direction, while either the hub 37 of the lever 22 105 or the nuts 34 and 35 serve to limit the end-

wise movement of shaft 18 in the opposite direction. The nuts 34 and 35 may also be employed to adjust the tension upon the spring 33.

It will be noted that the yielding pressure of the cams 31 against the faces of the cams 28 results in yieldingly holding the disk 25 in a plane at an angle of substantially thirty to forty-five degrees relative to the axis of the shaft 18, or at one extreme position of inclined adjustment of the disk 25 relative to the shaft 18, and that force exerted upon the disk 25 and cams 28 tending to force the disk 25 toward the opposite limit of its movement and the sleeve endwise away from the disk 25, would result in the sleeve 30 yielding endwise along the shaft 18 until the nose or point of the cams 28 had passed the nose of the cams 31, whereupon the spring would assist the moving force to complete the movement of the disk 25 to the opposite extreme of its movement, and in fact the sleeve 30 and spring 33 would serve to complete the movement of the disk to the opposite extreme of its movement in the absence of a moving force, once the nose of the cams 28 have passed across the nose of the cams 31. In other words the sleeve 30 and spring 33 serve to hold the disk 25 yieldingly at one or other of the extremities of its adjustment relative to the shaft 18.

A transmitting ring 40 is journaled upon the periphery of the disk 25, and held in place thereon by means of a flange 41 formed on the ring 40 which embraces one edge of the disk 25, and a separate ring or flange 42 which is bolted to the ring 40 and embraces the opposite edge of the disk 25. Above the shaft 18 the ring 40 is provided with a tooth or projection 43 which engages between the forked ends of a crank arm 44, which is rigidly attached to the lower end of a vertically disposed target or signal shaft 45, which is journaled in a bearing 46 formed in the upper section 16 of the casing. The ring 40 below the shaft 18 is provided with a ball 47 which is seated in a socket 48 in one end of a short link 49, the opposite end of which link is pivotally connected at 50 to one end of a connecting bar 52 which slides endwise through a guideway 53 in the lower casing section 15, and which connecting bar 52 is operatively connected at its opposite end 54 outside of the switch casing with the railway switch to be actuated thereby in the usual manner. Ribs 62 carried by section 15 act as lateral guides and supports for link 49 and bar 52. In Figs. 7, 8 and 9 I have illustrated diagrammatically different positions of the switch apparatus, from which it will be apparent that when the hand lever 22 is employed to throw the switch, the shaft 18 and disk or rocker member 25 retain their relative posi-

tion but turn or move through one hundred and eighty degrees with the axis of shaft 18 as a center, or from position Fig. 7 to position Fig. 8 while the ring 40 does not rotate, but is shifted through an inclination of sixty or ninety degrees as the case may be due to the rotation of the disk 25 therein. This inclination of the ring 40 serves to throw the switch through the endwise movement of the connecting bar 52, and at the same time the target shaft 45 is shifted through an arc of ninety degrees by the tooth 43 and crank arm 44. When, however, the switch is thrown by a locomotive passing along the track, the connecting bar 52 is forced endwise by the movement of the switch, say from the position Fig. 7 to the position Fig. 9, which forces the ring 40 and with it the disk 25 and cams 28 turning on the pin 26 to a position which is different relative to the shaft 18, until the nose of the cams 28 pass across the nose of the cams 31, whereupon the spring tension of the spring 33 completes the movement and shifts the disk 25 to the opposite extremity of its movement, carrying the ring 40 therewith and completing the throw of the switch and connecting bar 52, and also completing the throw of the target shaft 45, but causing no rotation of the shaft 18, and no movement of the lever 22.

The apparatus herein shown and described is capable of considerable modification within the scope of the claims without departing from the spirit of my invention.

What I claim is:

1. An automatic switch stand comprising a switch stand casing, an actuating shaft journaled in said casing and provided with a manually operable lever exteriorly of said casing, a rocker member carried by and pivotally mounted upon said actuating shaft and having a limited movement relative to said actuating shaft, a cam member carried by and movable endwise relative to said actuating shaft and having an engaging face held in resilient engagement with a face carried by said pivotally mounted rocker member, a switch actuating connecting rod movable relative to said casing, and means operatively connecting said pivotally mounted rocker member with said switch actuating connecting rod, whereby said connecting rod is adapted to be actuated by said pivotally mounted rocker through rotation of said actuating shaft, and said pivotally actuated rocker is adapted to be rocked from one position to another relative to said actuating shaft through actuation of said switch actuating connecting rod by an automatically actuated switch.

2. An automatic switch stand comprising a switch stand casing, an actuating shaft journaled in said casing and provided with a manually operable lever exteriorly of said

- casing, a rocker member carried by and pivotally mounted upon said actuating shaft and having a limited movement relative to said actuating shaft, a cam member carried by and movable endwise relative to said actuating shaft and having an engaging face held in resilient engagement with a face carried by said pivotally mounted rocker member, a switch actuating connecting rod movable relative to said casing, a target shaft journaled to said switch stand and adapted to indicate the position of a switch to which said switch actuated connecting rod is connected, and means operatively connecting said pivotally mounted rocker member with said target shaft and with said switch actuating connecting rod whereby said target shaft and switch actuating connecting rod are adapted to be actuated by said pivotally mounted rocker member through rotation of said actuating shaft, and said pivotally actuated rocker member and said target shaft are adapted to be shifted from one position to another relative to said actuating shaft through actuation of said switch actuating connecting rod by an automatically actuated switch.
3. An automatic switch stand comprising a switch stand casing, an actuating shaft journaled in said casing and provided with a manually operable lever exteriorly of said casing, a rocker member carried by and pivotally mounted upon said actuating shaft and having a limited movement relative to said actuating shaft, a cam member carried by and movable endwise relative to said actuating shaft and having an engaging face held in resilient engagement with a face carried by said pivotally mounted rocker member, a switch actuating connecting rod mounted to move endwise relative to said casing, and means operatively connecting said pivotally mounted rocker member with said switch actuating connecting rod to actuate endwise thereof said switch actuating connecting rod through rotation of said actuating shaft and pivotally mounted rocker member, and to shift said pivotally mounted rocker member relative to said actuating shaft when said switch actuating connecting rod is shifted endwise by an automatically actuated switch.
4. An automatic switch stand comprising a switch stand casing, an actuating shaft journaled in said casing and adapted to be positively rocked through a partial rotation, a rocker member mounted upon said shaft and having a limited angular adjustment relative to said actuating shaft, means carried by said actuating shaft to yieldingly hold said rocker member at either extremity of its adjustment relative to said actuating shaft, a switch actuating connecting rod, and means operatively connecting said rocker member to said connecting rod and adapt-
- ed to actuate said connecting rod when said actuating shaft and rocker member are rocked from one extremity of the movement of said shaft to the other, and adapted to rock said rocker member relative to said actuating shaft when said connecting rod is shifted by an automatically actuated switch.
5. An automatic switch stand comprising a switch stand casing, an actuating shaft journaled in said casing and adapted to be positively rocked through a partial rotation, a rocker member mounted upon said shaft and having a limited angular adjustment relative to said actuating shaft, means carried by said actuating shaft to yieldingly hold said rocker member at either extremity of its adjustment relative to said actuating shaft, a target shaft journaled to said switch stand casing, a switch actuating connecting rod, and means operatively connecting said rocker member to said target shaft and to said connecting rod, and adapted to actuate said target shaft and connecting rod when said actuating shaft and rocker member are rocked together from one limit of movement of said shaft to the other, and adapted to actuate said target shaft and to rock said rocker member relative to said actuating shaft when said connecting rod is shifted by an automatically actuated switch.
6. An automatic switch stand comprising a switch stand casing, an actuating shaft journaled in said casing and adapted to be positively rocked through a partial rotation, a rocker member mounted upon said shaft and having a limited angular adjustment relative to said actuating shaft, means carried by said actuating shaft to yieldingly hold said rocker member at either extremity of its adjustment relative to said actuating shaft, a target shaft journaled to said switch stand casing, a switch actuating connecting rod, and means comprising a ring member journaled upon the periphery of said rocker member operatively connecting said rocker member to said target shaft and to said connecting rod, and adapted to actuate said target shaft and connecting rod when said actuating shaft and rocker member are rocked together from one limit of movement of said shaft to the other, and adapted to actuate said target shaft and to rock said rocker member relative to said actuating shaft when said connecting rod is shifted by an automatically actuated switch.
7. An automatic switch stand comprising a switch stand casing, an actuating shaft journaled in said casing and provided externally of said casing with a manually operable lever adapted to rock said shaft through a partial revolution, a member pivotally mounted upon said actuating shaft within said casing and having a limited rocking movement relative to said actuating shaft, a resiliently energized member adapted to

normally hold said rocking member at one or other extremity of its rocking movement relative to said actuating shaft, a target shaft journaled to said casing, a switch actuating connecting rod movably mounted relative to said casing, and means operatively connecting said target shaft and said connecting rod to said rocker member, and adapted to actuate said target shaft and connecting rod when said actuating shaft and

rocker member are rocked by said manually operable lever and adapted to actuate said target shaft and to rock said rocker member relative to said actuating shaft when said connecting rod is automatically actuated through automatic actuation of a switch to which it is connected.

In testimony whereof I have affixed my signature.

WALLACE M. GRAY.
